UNITED STATES PATENT OFFICE.

LAROE M. COLLINS, OF LEBANON, NEW HAMPSHIRE.

DESIGN FOR BAND-SAW FRAME.

Specification forming part of Design No. 6,803, dated August 19, 1873; application filed April 11, 1873.

To all whom it may concern:

Be it known that I, LAROE M. COLLINS, of Lebanon, of the county of Grafton and State of New Hampshire, have invented or produced a new Ornamental Configuration or Design for a Band-Saw Frame; and do hereby declare the same to be duly represented in the accompanying drawing, the said drawing being a perspective elevation of it.

The base part A of such frame usually supported on legs B B, of proper shape, is a straight bar, from one end of which springs upward a tapering neck, C C, curved in part as shown, the remainder extending over and parallel, or about so, to the top of the part A. The base

as well as the neck are paneled, while the edges of the panels, base, and neck are bounded by moldings, as shown. The front end of the neck terminates in a vertical cylinder or cylinder-tube, D, and the neck is surmounted by a bracket, E, having the form as shown.

The design includes the parts A C D E, formed and paneled as represented.

I claim as my invention or production—

The said ornamental design or configuration for a band-saw frame.

LAROE M. COLLINS.
